PUMPING MECHANISM.

1,028,338.

Specification of Letters Patent.

Patented June 4, 1912.

Application filed December 15, 1910. Serial No. 597,436.

To all whom it may concern:

Be it known that we, AUGUSTUS ELLSWORTH, residing at Oilcenter, and AMBROSE F. ABBOTT and ROY C. ABBOTT, residing at Bakersfield, county of Kern, State of California, citizens of the United States, have invented new and useful Improvements in Pumping Mechanisms, of which the following is a specification.

- 10 This invention relates to a device for pumping or flowing oil or other liquids out of the well; and it refers particularly to a device for accumulating gas pressure sufficient for forcing the liquid to the surface.
- 15 We are aware that certain devices have heretofore been designed for the purpose of raising oil through a small height by gas pressure, and especially for aiding the ordinary pumping apparatus in raising the oil.
- 20 But no attempt has been made to accumulate the gas pressure so that it would force the oil to any great elevation. In a large majority of oil wells the gas pressure is comparatively low, in a great number of cases 25 being less than ten pounds per square inch. There are some wells in which the gas pressure is sufficient to blow the oil and piping out of the hole, but these wells are ordinarily uncontrollable.
- 30 It is the object of our invention to provide a device or mechanism which will accumulate the gas pressure in an ordinary well sufficiently to raise the oil to the surface in large quantities. With our device we 35 have been able to pump wells up to a depth of two thousand feet where before the accumulation of the gas, the pressure was normally insufficient to raise a column of oil to that height or to move an ordinary
- 40 steam gage. Thus our invention is seen to radically differ from those inventions which merely utilize the normal gas pressure for raising the oil a few feet. And another feature of difference is this, that in the old 45 mechanisms the movement of the oil by gas pressure was ordinarily intermittent, while in our device the oil flows evenly and continuously until either the oil or gas has been exhausted from the well.
- 50 The utility of our invention will be obvious. The means now in use for pumping wells involves an extended and complicated mechanism and requires the attendance of at least one man, or two men if the pumping 55 is continued. Our device will pump more

oil from a well than is ordinarily possible with a reciprocating pump, as the pump makes an intermittent flow while the new device makes a continuous flow; and our device will do this without careful attention. 60

In the accompanying drawings Figure 1 is a sectional view showing our device applied to a well. Fig. 2 is a cross section taken on line 2—2 of Fig. 1.

In the drawings 6 designates the casing 65 of a well in which oil or other liquid has risen to any point below the upper end of the casing and is required to be removed therefrom. A head 7 is provided for the upper end of the casing so that no gas shall 70 escape except as is especially provided for. A nipple 8 leads upwardly from head 7 and connects with a T-fitting 9 to which a valve 10 is connected. Valve 10 is for the purpose of relieving the gas pressure in the 75 upper part of the casing when the gas pressure accumulates more than is desirable or safe. A gage 11 may be used for indicating the pressure, or a safety valve may be substituted for the gage and hand valve so that 80 the pressure may be automatically relieved when it reaches a certain point above that required for pumping the well. A lead pipe 12 passes upwardly through the well and through nipple 8 and T-fitting 9 and is 85 connected to a T-fitting 13 on its upper end, from whence pipe 14 passes for leading off the oil which is pumped from the well, a valve 15 controlling the flow of oil. At the top of T-fitting 13 a plug 16 is inserted, 90 being removable so that a rod or other long article may be passed down pipe 12 to remove any sand or other foreign matter which might clog the pipe. At the lower end of pipe 12 an inverted cone shaped foot 95 piece 20 is attached. Foot piece 20 is preferably made of thin metal and its lower edge is either of such diameter as to leave an annular space between it and the casing, or preferably it touches the casing and is provided with perforations 21 which extend above and below the line of contact so that the gas may pass upwardly through the perforations into the space in the casing above foot piece 20. 100

In operation, the foot piece and lead pipe are lowered so that the foot piece stands with its lower edge within the oil. This is all that is necessary, although a deeper placement of the foot piece will insure better 105 110

operation. The gas from the oil and other sources, passing up through the oil passes up the sides of the casing and through apertures 21 into the space illustrated. Here the 5 pressure accumulates (the time usually taken being a few hours) and presses down on the oil surface with sufficient force to elevate the oil through pipe 12 to the surface. The pressure required will vary some- 10 what, but it is always much less than the pressure normally required to raise a solid column of oil of equivalent height. The liquid will flow continuously as long as there is oil in the well above the lower edge of the 15 foot piece 20, coming to the top of the well in frothy form. The foot piece can be lowered as the oil level falls if the oil is pumped from the well faster than it flows in. It will be understood, however, that 20 when the pump is started with the foot piece in the oil, the upwardly flowing stream will serve to continuously raise the oil until, when the stream ceases, the normal level of the oil will fall as much as two hundred feet 25 below the foot piece.

Sometimes an agitation of the oil and gas is needed to cause them to flow, in which case the foot piece may be moved up and down through the oil and the oil and gas 30 agitated, causing a renewal of the flow.

From the foregoing it will be seen that our invention is not limited to the specific form described, but only to such equivalent results. The configuration of the foot piece 35 may be varied and the connections at the top of the well may also be changed.

Having described our invention, we claim:

1. In an oil pumping mechanism for wells 40 the combination of an outer casing, a cap member or cover threaded to said casing, a centrally disposed vent device for natural gas attached to said cap member or cover, a lead pipe of relative small diameter passing through said vent device and into said 45 casing down to and within the oil in the well, a flaring cone-shaped mouth at the lower end of said lead pipe, said flaring mouth portion touching or nearly touching the aforesaid casing and serrations or gas 50 passages around the lower end of said flaring on cone-shaped mouthpiece.

2. In an oil pumping mechanism for wells, 55 the combination of an outer casing, means on said outer casing to accumulate within said casing the natural gas arising from the oil in the well, means to register the pressure and means to regulate the amount of said accumulation of natural gas attached to said outer casing, a centrally disposed

lead pipe passing within said casing down 60 to and within the oil in the well, an enlarging mouthpiece to said lead pipe touching said outer casing, rectangular-shaped serrations around the lower edge of said enlarged mouthpiece, said serrations extending 65 above and below the portion of the enlarged mouthpiece which touches the outer casing, and said serrations allowing the passage of the natural gas arising out of the oil in said well to said accumulating chamber. 70

3. In a device of the character described, the combination with a well casing, of a discharge pipe and a gas collecting device mounted upon the lower end of said discharge pipe of substantially conical form, 75 the small end of said collecting device being connected to said discharge pipe, said collecting device being formed to permit upward passage of fluid between its lower edge and the well casing.

4. In a device of the character described, the combination with a well casing, of a discharge pipe, a gas collecting device mounted upon the lower end of said discharge pipe of substantially conical form, 85 the small end of said collecting device being connected to said discharge pipe, and the large end of said collecting device being of substantially equal diameter with the interior of the well casing and being formed 90 to permit the upward passage of fluid between itself and the well casing.

5. In a device of the character described, the combination with a well casing, of a discharge pipe, and a gas collecting device 95 mounted upon the lower end of said discharge pipe of substantially conical form, the small end of said collecting device being connected to said discharge pipe and the large end of said collecting device being of 100 substantially equal diameter with the interior of the said well casing, the lower end of said collecting device being disposed within a body of liquid within the well casing and being formed to permit the upward 105 passage of some of said liquid past said collecting device.

In witness that we claim the foregoing we have hereunto subscribed our names this 16th day of November, 1910.

AUGUSTUS ELLSWORTH.
AMBROSE F. ABBOTT.
ROY C. ABBOTT.
